INSPECTION MEANS

Leo J. Molloy, Baltimore, Md., and Louis K. Morrison, Norfolk, Va.

Application May 22, 1936, Serial No. 81,310

11 Claims. (Cl. 116—114)

This invention relates to means for facilitating the inspection and determination of conditions within tanks, receptacles, and systems, for example, those in the art relating to fire extinguishers and systems.

The invention has particular application to fire extinguishing spray tanks, apparatus and systems, and it enables an observer to readily determine if the fire extinguishing tank or apparatus has had its fire extinguishing charge periodically renewed or replaced. It will be evident, however, from an understanding of this invention that it has application in certain cases to tanks, receptacles and the like, other than those used in extinguishing fires, where it is desirable to accurately and readily determine the conditions existing within the tanks, receptacle or the like.

In order to maintain portable fire extinguishers, or other fire extinguishing systems and apparatus, in a condition of maximum efficiency, it is generally necessary to periodically change or renew their fire extinguishing charges. This necessity is well recognized; for example, the fire insurance companies require their policy holders to regularly renew the contents of their (the policy holder's) fire extinguishers. If the policy holders do not comply with this requirement, their insurance protection is subject to revision or termination. Users of fire extinguishers, therefore, issue instructions that the fire extinguishing charges should be periodically renewed. These instructions are in part the result of a desire for efficient fire protection and in part the result of a desire to preserve the fire insurance contract.

Despite any rule or instruction that an official (whether of a factory, railroad or business house), may issue to his employees with regard to conditioning of his company's fire extinguishing apparatus, the employees, as shown by experience, will not, or fail to, change or renew the fire extinguishing charge at one or another of the times designated for this conditioning of the apparatus. Heretofore, it has been difficult to detect this evasion of the company rules, as the charge was not possessed of distinguishing characteristics to indicate when it had been placed in the fire extinguishing apparatus or when it was to be renewed; and inspection required opening or discharge of the fire extinguishing apparatus.

It is, therefore, an object of our invention to provide a fire extinguishing substance or charge which will exhibit a visible characteristic to in-

dicate its period of maximum effectiveness and the time when it was placed in the fire extinguishing apparatus or system.

A further object is to provide fire extinguishing apparatus or other liquid containing systems with light-transmitting means which will permit observation and illumination of the visible characteristics of the fire extinguishing charge or substance within the apparatus or system.

Another object is to provide an improved inspection attachment for use with tanks, receptacles, and other apparatus, where it is desired to observe the conditions existing therein.

It is a further object to provide means which will facilitate the determination as to whether the contents of a particular fire extinguishing apparatus or system has been periodically renewed, where such renewal is essential to maintain the apparatus in a condition of maximum efficiency.

Other objects, uses and advantages of this invention will be more apparent from the following description and the appended drawing wherein,

Fig. I is an elevational view of a conventional portable fire extinguisher provided with an embodiment of this invention, parts of the extinguisher being broken away for the purposes of illustration.

Fig. II is an enlarged vertical cross sectional view of the inspection window shown in Fig. I, being taken on line II—II of Fig. I.

Fig. III is a perspective view of the thimble element shown in Figs. I and II.

Referring to the drawing, the fire extinguisher 1 is of the conventional portable type which is provided with a fluid charge 2 comprising a solution of sodium bicarbonate and with a small bottle of a suitable acid (not shown). The invention, however, may obviously be applied to other types of fire extinguishing apparatus.

The fire extinguisher 1 has the usual bottom wall 3 which is set back or spaced from the bottom edges of the extinguisher side walls to provide a recessed base for the fire extinguisher.

The charge 2, whether it is a solution of sodium bicarbonate or some other fire extinguishing substance, has in general a maximum effectiveness of only limited duration. The practice, therefore, is to periodically renew or replace the charge. The stability or resistance to deterioration of the charge 2 generally determines the length of the period it may be left in the fire extinguishing apparatus without the efficiency of the apparatus falling below a desired minimum. Heretofore,

it has been difficult to determine if the charge 2 has been left in the fire extinguishing apparatus beyond the limit of its period of maximum effectiveness. It is, therefore, a feature of this 5 invention to provide fire extinguishing charges which have visible identifying characteristics for indicating whether the charge is new or has been left in the apparatus beyond its period of maximum effectiveness. The characteristics referred 10 to may be the color of the charges. This color characteristic may be secured by the addition of a suitable dye, or other color producing agent, to the charge 2 at the time it is prepared for the fire extinguishing apparatus.

15 For the purposes of a specific example, it may be assumed that the maintenance of fire extinguishing apparatus in a condition of maximum efficiency requires renewal of the fire extinguishing charge 2 every year. According to a preferred embodiment of this invention, different 20 colors serve to distinguish the different fire extinguishing charges to be used during successive years, and if any charge is not renewed at the end of a year, its color characteristic will disclose this fact to an inspector during his round 25 of inspection.

In order that the color or other indicating 30 characteristic of the charge 2 may be observed without opening the fire extinguishing apparatus, an inspection window is provided in a wall 35 of the extinguisher. This inspection window, which may be placed in the bottom wall 3 of the apparatus as shown in the drawing, has a hollow cup or thimble-shaped member 10 of transparent glass, or of other suitable light-transmitting material, through which the indicating characteristics of the charge 2 are visible. The closed end 11 of the thimble-shaped member 10 is tapered, or otherwise suitably shaped, for a purpose 40 to be described, and the open end of the thimble member 10 has a flange 12. The thimble member 10 is mounted in a frame member 13, which has inner and outer annular shoulders as shown 45 in Fig. II. A ring 14 having threaded engagement with the interior wall of the frame member 13 serves to clamp the thimble flange 12 and a pair of ring-shaped gaskets 15 and 16 (of any suitable material) against the internal shoulder 50 of the frame member 13 and to maintain the thimble member 10 and frame member 13 in assembled relation. The gaskets 15 and 16 are positioned at opposite sides of the thimble flange 12 to seal the joint and to protect the thimble flange 12. The inspection window is also provided 55 with a gasket 17 and a clamping ring 18, the latter having threaded engagement with the external wall of the frame member 13.

The inspection window, as described above, 60 comprises a unit which may be installed in extinguishers already in service or in extinguishers at the time of their manufacture. In order to install the inspection window unit, a suitable aperture is made in a wall, for example, the bottom 65 3, of the extinguisher, and the frame member 13 is inserted in the aperture. The ring 18 may now be positioned to clamp the extinguisher wall 3 and gasket 17 against the external shoulder of the frame member 13. The open end of the thimble member 10 is now in communication 70 with the interior of the fire extinguisher so that part of its charge 2 will flow into the thimble member 10 where it may be conveniently inspected.

The closed end 11 of thimble 10, when the 75 inspection window unit is installed in the fire ex-

tinguisher, will project beyond the bottom wall 3 but within the limits of the extinguisher as defined by the projecting side walls constituting its base. The projecting side walls, while affording a large measure of protection against accidental damage to the transparent thimble 10, will not interfere with the examination of the thimble member 10 and its contents nor prevent examination at close range. The fire extinguisher base does prevent an observer from illuminating and 10 inspecting the thimble contents along lines normal to the longitudinal axis of the thimble member 10. The tapered end 11 of the thimble, however, overcomes this drawback attendant the placement of the inspection device in an out-of- 15 the way and protected position. This tapered end 11 permits illumination, as by flashlight, and observation from positions (such as indicated by the letters A and B) beyond the bottom edges of the extinguisher base and along lines (shown 20 in the drawing as extending between the tapered end 11 and the positions A and B) approximately normal to the tapered end 11. The examination may, therefore, be readily conducted along lines normal to the inner and outer surfaces of the 25 thimble member 10, and will not be interfered with by light refraction which occurs when a beam of light passes obliquely from one medium into another. The closed end 11 may obviously be provided with other suitable shapes, such as 30 hemispherical, which will serve the same purpose as the tapered form of thimble end.

The inspection device of this invention will 35 obviously facilitate inspections and eliminate the necessity for moving or handling the extinguisher provided with same even if the extinguisher is hung in a difficultly accessible place, such as when it is within a wall recess or mounted on a bracket in a corner of a room.

The present invention also obviously has 40 application to other than fire extinguishing apparatus and is useful wherever the problems solved thereby are present.

It will be understood that the foregoing description is illustrative, and that the appended 45 claims are intended to cover such other embodiments as are within the scope of the invention.

We claim:

1. The combination with a portable fire extinguisher having its bottom wall set back from 50 the bottom edges of its side walls and containing a fire extinguisher charge which is to be periodically renewed to maintain the extinguisher in a condition of maximum efficiency and which has a visible characteristic to indicate effectiveness, 55 of an inspection window in the form of a light-transmitting thimble shaped member supported by said bottom wall with the open end of the member communicating with the interior of the extinguisher to permit a part of said charge to 60 enter the member, said member having a closed end extending below said bottom wall but within the limits of the extinguisher defined by said side wall and bottom edges, said closed end being suitably shaped at its periphery to permit illumination and inspection of the contents in said member from beyond said side wall bottom edges and along lines inclined with respect to the axis of the member but approximately normal to the surface at said periphery.

2. An inspection device for use with a fire extinguisher or extinguishing system having a fire extinguishing charge which is to be periodically renewed to maintain the extinguisher in a condition of maximum efficiency and which has a 75

visible characteristic indicative of its period of maximum effectiveness, said device comprising a frame member having internal and external shoulders and adapted to be set within an opening in a wall of a fire extinguisher, a transparent hollow thimble-shaped member having a flanged open end set within said frame member and its closed end extending beyond said frame member, means to clamp the flange of said thimble-shaped member against said internal shoulder, and means to clamp said external shoulder to said fire extinguisher wall.

3. An inspection device for use with a fire extinguisher or extinguishing system having a fire extinguishing charge which is to be periodically changed to maintain the extinguisher in a condition of maximum efficiency and which has a visible characteristic indicative of its period of maximum effectiveness, said device comprising a frame member having internal and external shoulders and adapted to be set within an opening in a wall of a fire extinguisher, a transparent hollow thimble-shaped member having a flanged open end set within said frame member and its closed end extending beyond said frame member, a ring having threaded engagement with the interior wall of said frame member to clamp the flange of said thimble-shaped member against said internal shoulder, and a ring having threaded engagement with the exterior wall of said frame member to clamp said external shoulder to said fire extinguisher wall.

4. An inspection device for use with a fire extinguisher or extinguishing system having a fire extinguishing charge which is to be periodically changed to maintain the extinguisher in a condition of maximum efficiency and which has a visible characteristic indicative of its period of maximum effectiveness, said device comprising a frame member adapted to be placed at an opening in a wall of a fire extinguisher, a transparent hollow thimble-shaped member, and a pair of clamping rings having threaded engagement with said frame member to separately clamp said thimble-shaped member and extinguisher wall to said frame member.

5. An inspection device for attachment to receptacles, tanks and the like comprising a frame member having internal and external shoulders and adapted to be set within an opening in a wall of said tank, a transparent hollow thimble-shaped member having a flanged open end set within said frame member, said hollow member having its closed end tapered and extending beyond said frame member, a ring having threaded engagement with the interior wall of said frame member to clamp the flange of said hollow member to said internal shoulder, and a ring having threaded engagement with the exterior wall of said frame member to clamp said external shoulder to said tank wall.

6. The combination with a portable fire extinguisher of the type having its interior normally open to the atmosphere and adapted to receive charge components such as a solution of sodium carbonate and a substance for reacting therewith which require periodic renewal to maintain the extinguisher in a condition of maximum efficiency and which upon inversion of the extinguisher react to liberate a pressure producing gas for expelling the extinguisher charge under pressure, of an inspection chamber for a wall of the extinguisher, said chamber having a closed end projecting beyond said wall, and an opening in communication with the interior

of the extinguisher to permit part of said charge to enter said chamber, said chamber having at least a portion thereof of light-transmitting material to permit observation of the chamber contents from without the extinguisher.

7. The combination with a portable fire extinguisher of the type having its interior normally open to the atmosphere and adapted to receive charge components such as a solution of sodium carbonate and a substance for reacting therewith which require periodic renewal to maintain the extinguisher in a condition of maximum efficiency and which upon inversion of the extinguisher react to liberate a pressure producing gas for expelling the extinguisher charge under pressure, of an inspection window for a wall of the extinguisher, said window being in the form of a light-transmitting thimble-shaped member having its closed end projecting beyond said wall and its open end in communication with the interior of the extinguisher to permit part of said charge to enter said member for inspection from without the extinguisher.

8. The combination with a portable fire extinguisher of the type having its interior normally open to the atmosphere and adapted to receive charge components such as a solution of sodium carbonate and a substance for reacting therewith which require periodic renewal to maintain the extinguisher in a condition of maximum efficiency and which upon inversion of the extinguisher react to liberate a pressure producing gas for expelling the extinguisher charge under pressure, of an inspection chamber for a wall of the extinguisher, said chamber having a closed end projecting beyond said wall, and an opening in communication with the interior of the extinguisher to permit part of said charge to enter said chamber, said chamber having areas of light transmitting material and in different planes to permit illumination and observation of the contents within said chamber from different points having spaced relation about the chamber.

9. The combination with a portable fire extinguisher of the type having its interior normally open to the atmosphere and adapted to receive charge components such as a solution of sodium carbonate and a substance for reacting therewith which require periodic renewal to maintain the extinguisher in a condition of maximum efficiency and which upon inversion of the extinguisher react to liberate a pressure producing gas for expelling the extinguisher charge under pressure, of light-transmitting means comprising a thimble-shaped member secured to the bottom wall of the extinguisher and having its interior communicating with the interior of said extinguisher to permit part of said charge to enter said member for inspection from without the container.

10. The combination with a portable fire extinguisher of the type having its interior normally open to the atmosphere and adapted to receive charge components such as a solution of sodium carbonate and a substance for reacting therewith which require periodic renewal to maintain the extinguisher in a condition of maximum efficiency and which upon inversion of the extinguisher react to liberate a pressure producing gas for expelling the extinguisher charge under pressure, of an inspection window in the form of a light-transmitting thimble-shaped member having its open end communicating with the interior of the extin-

- guisher to permit a part of the charge to enter the member, said member having a closed end projecting beyond a wall of the extinguisher, said closed end being suitably shaped at its periphery to permit illumination and inspection of the charge in the member from the sides thereof and along lines inclined with respect to the axis of the member but approximately normal to the surface at said periphery.
- 10 11. The combination with a portable fire extinguisher of the type having a reservoir open to the atmosphere and adapted to contain charge components which react upon inversion of the extinguisher to liberate a gas for exerting pressure to discharge the extinguisher contents and which require periodic renewal to maintain the

extinguisher in a condition of maximum efficiency, of a solution stored in said reservoir as one of said charge components, said solution being provided with a coloring material that is arbitrarily selected as indicative of the date when the solution was placed in the extinguisher, and transparent inspection means in communication with the interior of the extinguisher reservoir and projecting outwardly from a wall thereof to contain and to present to view exteriorly of the extinguisher a portion of the solution contained within the extinguisher in order to determine by the color of the solution the length of time it has remained in the extinguisher. 5 10
